HAROLD H. YOUNG AND EARLE A. RYDER, OF KEYPORT, NEW JERSEY.

SUPPORT FOR ELECTRICAL APPARATUS.

Application filed March 26, 1924. Serial No. 702,033.

To all whom it may concern:

Be it known that we, HAROLD H. YOUNG and EARLE A. RYDER, both citizens of the United States, and residents of Keyport, in the county of Monmouth and State of New Jersey, have invented certain new and useful Improvements in Supports for Electrical Apparatus, of which the following is a specification, reference being had to the accompanying drawings, forming part of this specification.

This invention relates to radio apparatus in general and more specifically to the receiving type of radio systems known as multi-tube sets and in which a number of controlling or operating instruments are usually required.

The present invention features an improved means by which a multiplicity of controlling or operating instruments may be formed into a unitary assemblage, and a novel method of so grouping the same on a supporting member as form a compact self-contained unit is herein disclosed.

An object of the invention is to provide a means whereby the principal parts of a radio signalling apparatus such as variable condensers, vacuum tubes, coils, transformers etc., together with their connecting members or lead wires may be pre-assembled into a unit for later introduction into a suitable case or cabinet.

It is one of the prime requisites for the efficient operation of a signalling set especially where high frequency is employed, to reduce the length of the various connecting wires to a minimum in order to eliminate stray fields and undesirable capacity or magnetic coupling.

Therefore it is a further object of this invention to provide a means whereby such instruments may be brought into closer relationship than heretofore for the purpose of so reducing the length of the necessary lead wires as to substantially eliminate such undesired effects.

In the present day most radio instruments are provided with their individual supporting members, as for example, the variable condensers are equipped with end plates of

dielectric material, the vacuum tubes require each a separate socket for support and operation.

To this end it is a still further object of the present invention to provide a simple inexpensive method of construction in which ordinary commercially available material may be used to fabricate a support for a multiplicity of such instruments without resorting to the use of expensive dies or molds for forming sockets or other equipment of a like nature.

These various objects we achieve by employing a pair of supporting members readily constructed from standard material and in which no dies, molds or special machinery are required to fabricate the same.

With the construction as herein disclosed it becomes possible to so position the instruments relatively to one-another that the connecting wires may be short and direct and disposed so that they will be very little in evidence. It will be readily understood that with such material reduction in the length of the wiring system, stray coupling will be greatly reduced or entirely eliminated and the general appearance much enhanced.

It has been customary in the past when constructing an apparatus for radio signalling, to mount or secure each instrument individually to a base board or panel and to then establish the necessary connections therebetween. Such a procedure usually resulted in rather a complex wiring system which is objectionable. Furthermore with the conventional manner of construction sub-assemblies are manifestly impracticable and such sets are usually completely assembled at one time.

With the form as herein shown and described we have provided a means whereby either a partial or a complete circuit may be assembled in advance for attachment to a base board or panel at some future time.

Still another object of the invention is to provide a supporting means for radio instruments in which the parts are of such construction as to permit of them being distributed to the trade in a "knocked down" 100

condition, as will be more fully described hereinafter.

To these and other ends, the invention consists in certain improvements and the combination and arrangement of parts, all as will be more fully hereinafter described, the features of novelty being pointed out particularly in the claims at the end of the specification.

10 In the drawings:—

Figure 1 is a plan view of the invention. Figure 2 is a front elevation.

Figure 3 is an end view of Figs. 1 and 2 as looking from the right hand end.

15 In the present instance 10 and 11 designates a pair of upstanding spaced apart walls preferably formed of dielectric material such as bakelite and provided with a series of perforations 11^a for the reception 20 of portions of the instruments to be mounted thereon.

A plurality of variable condensers 12 are disposed between the walls 10 and 11 and secured thereto by means of the tie-bolts 13

25 which extend through the fixed plates of the condensers 12 and the perforations 11^a.

30 Alternately spaced with the condensers, provisions are made for the reception of a number of vacuum tubes, in which the transversely disposed rods 14 act in conjunction with the walls as a lateral support for the lower portion of the tubes 15. Springs 16 are secured to the walls by the screws 17 and are of such construction as to make 35 contact with the tube terminals 18 when the tubes are inserted in their respective openings. A means for holding the tubes in a relatively fixed position with the springs 16 is provided by the bayonet slots 40 19 formed in the wall 10 and adapted to receive the locking pin on the tube.

A top plate or cover portion 20 may be provided to insure the proper introduction of the tubes with reference to the springs 45 16 which would prevent the burning out of tubes by the inexperienced, or a metal ferrule may be inserted between the walls for the same purpose; this feature is however optional and not actually necessary for 50 the proper functioning of the device.

To the wall 11 there is secured in any suitable manner as by the bolts 13 a number of bosses 21 by which the unit may be attached to a panel 22 by means of the 55 screws as shown.

On the exterior of the walls 10, 11 a number of other instruments may be accommodated such as coils 23, transformers 24 and rheostats 25 and which can be secured in any preferred manner as by the brackets 29.

60 The filament lead wires 26, 27 are connected to the springs 16 as shown in Fig. 2 and are usually soldered. Other connections are made in a similar manner as shown

in Fig. 1 in which a lead 28 is brought from the condenser tie bolt to the spring 14 indicating a grid terminal.

It will be seen from the drawings that a number of instruments can be conveniently formed into a compact unit as hereinbefore described, and whereas there is shown in the present embodiment a plurality of variable condensers and tubes, it is to be understood however that the invention is not restricted in its scope to the exclusive use of such instruments as shown in the drawings nor to the manner of their disposition relative to one another. It will be appreciated that in radio apparatus employing a multiplicity of vacuum tubes it would be advantageous to form an exclusive tube supporting unit in the above described manner in which any number of tubes may be disposed adjacent to one-another and a similar unit constructed for the support of the condensers, etc. This would eliminate numerous tube sockets and other expensive material.

As a convenience to those who wish to "build their own" the supporting means, comprising the walls suitably perforated to accommodate a variety of instruments may be distributed commercially either singly or in pairs.

We have stated that the walls are preferably formed of dielectric material; it is however considered within the scope of this invention to form said walls of metal or any electrically conductive material and to suitably insulate the instruments therefrom as by non-conductive bushings; in fact a certain advantage may accrue in so constructing said walls and connecting them with a convenient ground wire. When formed of such material, the walls would act as a shield to prevent the effect of body capacity of the operator so annoying at times during the operation of a receiving set.

Variations may be resorted to within the scope of the invention and portions of the improvements may be used without the others.

Having thus described our invention, we claim:

1. In a radio signalling apparatus, the combination of a pair of flat elongated wall portions and a plurality of tie members therefor so spaced respectively as to permit of the introduction of vacuum tubes therebetween in a manner so that said wall portions and tie members will provide a lateral support for the same.

2. In apparatus of the class described the combination of a pair of flat elongated members of a width substantially equivalent to the height of the cylindrical base of a vacuum tube, said members spaced apart in fixed relation substantially equivalent to the

- diameter of said base, a plurality of transversely disposed tie members connecting said walls, some of said tie members adapted to support variable condensers, and the others of said tie members adapted to act in conjunction with said elongated members to form a lateral support for vacuum tubes. 5
3. In apparatus of the class described, a pair of flat wall portions of a width substantially equivalent to the height of the cylindrical base of a vacuum tube, said wall portions spaced apart in fixed relations substantially equal to the diameter of said base, spacing members secured to said walls and adapted to engage and sustain a plurality of vacuum tubes in operative positions between said members. 10
4. In a radio signalling apparatus, the combination with variable condensers and vacuum tubes, of a supporting means therefore, comprising a pair of elongated walls spaced in fixed relation so as to permit of the introduction of the condensers and tubes therebetween in a manner so that said walls will form a lateral support for said tubes, tie means connecting said walls, and resilient electrodes secured to said walls in a manner so as to make contact with portions of the tubes. 15
5. In apparatus of the class described, the combination of a pair of elongated members spaced apart in parallel, a plurality of tuning units disposed between said walls and relatively spaced apart longitudinally thereof, tie means extending through said walls and said units, means disposed between said tuning units in a manner so as to form in conjunction with said walls a lateral support for vacuum tubes, suitable resilient electrodes secured to said walls in a manner so as to extend therebetween for engagement with said tubes, and means for maintaining said tubes in a predetermined relation with said electrodes. 20
6. In apparatus of the class described, a supporting means for radio instruments comprising in combination, a pair of parallel elongated walls, means transversely disposed to maintain said walls in spaced relation, said walls so spaced apart as to provide for the introduction of a plurality of vacuum tubes therebetween in a manner so that said walls will laterally engage and support the tubes, and means on said walls for removably engaging said tubes and securing them in a predetermined position. 25
7. In apparatus of the class described, the combination of a pair of elongated wall portions horizontally spaced apart, tie means adapted to support variable condensers and to maintain said walls in a definitely spaced relation, means adapted to co-act with said wall portions in forming a lateral support for the lower portion of vacuum tubes, en-
- gaging means secured to said walls adapted to make electrical contact with the tube terminals, and means on said walls to insure a predetermined relation between said tubes and said engaging means. 30
8. In a radio instrument supporting unit, the combination with a panel, of a pair of elongated members spaced apart, a plurality of variable condensers supported therebetween, tie bolts transversely disposed for maintaining said members in spaced relation, some of said tie bolts so spaced longitudinally of said members as to form in conjunction therewith a lateral support for vacuum tubes provided with terminals, electrical contact means secured to said members and adapted to engage said terminals, means for removably engaging said tubes in a predetermined position, and means for securing the whole to the panel. 35
9. As a new article of manufacture, a radio instrument supporting unit comprising, a pair of flat parallel upstanding walls of elongated formation spaced apart in fixed relation and adapted to receive therebetween a plurality of tuning instruments and vacuum tubes in a manner so that said walls will form end plates for said instruments and a lateral support for said tubes, and tie members coacting with said walls to sustain said instruments and tubes in operatively fixed relation therewith. 40
10. In a device of the class described, the combination of a pair of spaced apart walls, tie means for holding said walls in relatively fixed relation for the reception of a plurality of control instruments, said tie means coacting with the walls in forming receptacles for the retention of one or more vacuum tubes in effective relation with said control instruments. 45
11. The combination with a radio signalling system, of a pair of spaced apart and relatively fixed sustaining members adapted for the reception of a plurality of control instruments, transversely disposed means adapted to coact with said members for the lateral support of further instruments, contact members secured to said walls to engage said instruments, electrical conductors secured to the contact members; and means to secure said sustaining members to a suitable support. 50
12. In a device of the class described, the combination of supporting wall portions adapted to receive and form a lateral support for a plurality of vacuum tubes, engaging means associated with said supporting wall portions for connecting said tubes into their respective circuits, and means on said walls adapted to insure a predetermined relation of said tubes to said engaging means. 55
13. In a device of the class described, the combination of a plurality of variable con-

densers supported in spaced apart relation on common end walls of insulating material, means transversely disposed of the walls and adjacent to said condensers adapted to co-
5 act with said walls to form a lateral support for one or more vacuum tubes between said condensers, and resilient contact means secured to the walls and adapted to engage terminals on the tubes to form electrical connection therewith. ¹⁰

Signed at Keyport in the county of Monmouth and State of New Jersey this 20th day of March A. D. 1924.
